UNITED STATES PATENT OFFICE.

EMERY ANDREWS, OF KENNEBUNK, MAINE, ASSIGNOR TO THE LEATHEROID MANUFACTURING COMPANY, OF SAME PLACE.

TRUNK-HINGE.

SPECIFICATION forming part of Letters Patent No. 312,947, dated February 24, 1885.

Application filed September 24, 1884. (No model.)

To all whom it may concern:

Be it known that I, EMERY ANDREWS, of Kennebunk, in the county of York and State of Maine, have invented a new and useful Improvement in Trunk-Hinges, of which the following, taken in connection with the accompanying drawings, is a specification.

My invention relates to the construction of trunk-hinges, and has for its object the production of a hinge which presents no sharp projecting corners or edges to catch and tear clothing; and it consists in certain novel features of construction, which will be readily understood by reference to the description of the drawings, and to the claims to be herein-after given.

Figure 1 of the drawings is an elevation of a trunk-hinge embodying my invention. Fig. 2 is a section of same on line $x-x$ on Fig. 1. Fig. 3 is a transverse section on line $y-y$ on Fig. 2, looking toward the joint; and Fig. 4 is an edge view of the leaf B, looking at the ears, to receive the joint-pin.

A and B are the two leaves of the hinge, the former being provided with the single ear a , and the latter with the two ears b , by means of which and the pin or rivet C the two leaves are pivoted together in the usual manner.

The leaves A and B are made considerably wider than the aggregate width of the three ears a b b , and have all of their outer corners rounded down to their under surface, as shown in Figs. 2, 3, and 4, so that there are no sharp corners presented to catch clothing or interfere with the sliding of the trunk upon which the hinge is secured along upon another trunk, or upon a carpeted floor when the trunk happens to lie upon the hinged side.

The thicker portions of the leaves A and B are chambered upon the under side, into which chamber projects the bosses c , through which the rivet or screw-holes d d pass, so as to form a solid bearing immediately around the fastening rivet or screw. In the narrower portion of each leaf is formed another rivet or screw hole, f , and intermediate between the holes f and d each leaf is provided with two sharp-pointed spurs, e , formed in one piece, or

integral with the leaf, which spurs enter the wall of the trunk or cover, and serve to register the hinge in the desired position before the rivets or screws are inserted, and to take a portion of the side-strain to which the hinge is subjected, and to that extent relieve the strain upon the fastening rivets or screws.

By making the aggregate width of the ears a b b considerably less than the width of those portions of the leaves A and B which are contiguous to said ears I am enabled to have the outer edges of the ears b b perpendicular to the under surfaces of the leaves without any possibility of clothing getting caught thereon or upon the ends of the pivot-pin C, which are protected by being inclosed between the projecting portions of the leaves A and B, as shown in Fig. 1.

It will be seen that the leaves A and B are made of the same thickness as the ears a and b for a considerable distance away from the pivotal connection thereof, and then are reduced in thickness, the outline of said reduction being a curved line, as shown in Fig. 1.

What I claim as new, and desire to secure by Letters Patent of the United States, is—

1. A hinge composed of the leaves A and B, connected together by the ears a b b and pin C, said leaves being made considerably wider than the aggregate width of the ears a b b , and having their outer surfaces curved or rounded down to their under surfaces, substantially as and for the purpose described.

2. A hinge the two leaves of which for a considerable portion of their lengths are made of a thickness equal to the thickness of the pivotal ears by which they are connected together, and have their outer faces curved or rounded and their inner faces chambered, substantially as described.

In testimony whereof I have signed my name to this specification, in the presence of two subscribing witnesses, on this 19th day of September, A. D. 1884.

EMERY ANDREWS.
